MOWER REAR GUARD

John M. Cope, Livonia, Mich., assignor to Sturdevant
Manufacturing Corporation, Livonia, Mich.

Filed Feb. 28, 1972, Ser. No. 230,177

Term of patent 7 years

Int. Cl. D15—03

U.S. Cl. D40—1 B

FIG. 1

FIG. 2

FIG. 4

FIG. 5

FIG. 6

FIG. 1 is a perspective view of a mower with rear guard attached, showing my new design.

FIG. 2 is a top plan view of the mower rear guard design illustrated in FIG. 1.

FIG. 3 is a side elevational view.

FIG. 4 is a front elevational view.

FIG. 5 is a rear elevational view.

FIG. 6 is a bottom plan view.

The broken lines representing the lawn mower are shown for illustrative purposes only.

I claim:

The ornamental design for a mower rear guard, as shown and described.
